UNITED STATES PATENT OFFICE.

ABRAHAM MORGAN, OF YOUNGSTOWN, OHIO.

DESIGN FOR A LIGHTNING-ARRESTER.

SPECIFICATION forming part of Design No. 30,109, dated January 31, 1899.

Application filed June 16, 1898. Serial No. 683,623. Term of patent 14 years.

To all whom it may concern:

Be it known that I, ABRAHAM MORGAN, a citizen of the United States, residing at Youngstown, in the county of Mahoning and State of Ohio, have invented a certain new and useful Design for Lightning-Arresters, of which the following is a specification, reference being had therein to the accompanying drawings.

10 My invention is a design for lightning-arresters; and it comprises the unitary design or configuration illustrated in the accompanying drawings, in which—

15 Figure 1 is a plan view of the design. Fig. 2 is a side elevation of the same, partly in section, and Fig. 3 is an end elevation, partly in section.

The design comprises a rectangular base 1, having a series of clamps 3 arranged in a row near each of its side edges. Each of these 20 clamps is twisted to form coils 4 and projecting ends 5, which latter are supported in the base. Adjacent to each of the clamps is a hole 6. Upon the under side of the base are parallel strips 7. 25

I claim—

The design for a lightning-arrester herein shown and described.

In testimony whereof I have affixed my signature in the presence of two witnesses.

ABRAHAM MORGAN.
